UNITED STATES PATENT OFFICE.

WILLIAM A. LEU AND EDWARD E. LEU, OF CHICAGO, ILLINOIS.

DISPLAY-BOARD STRUCTURE.

Application filed June 4, 1924. Serial No. 717,889.

The present invention relates to display board structures which are capable of varied use. Such structures commonly have a large flat display surface or "board" mounted on a flat frame which is supported by legs and braces connected with posts or other anchoring means in or upon the ground, buildings or other structures.

One object of the invention is to provide a main frame of such construction and arrangement that it may be shipped in "knocked down" condition and then readily assembled at the point of use without the assistance of skilled labor. Preferably, the main frame is made up of sections wherein angle iron is used for uprights and then the sections are secured together by transverse rods. Another object is to provide a backing for the main frame which although made up of sections has water proof joints so that it is used with enclosed display frames such as disclosed in our prior Patent No. 1,557,260, granted October 13, 1925, on application Serial No. 693,447, filed February 18, 1924, a well protecting, weather proof structure is provided. These backing sections are preferably metal sheets and their joints are made by folding the adjacent edges back upon themselves and then interlocking the folds. Another object is to provide readily adjustable bracing whereby the structure may be quickly and yet firmly set up on ground of regular or irregular contour. This bracing includes novel arrangements of telescoping braces and rods of varying adjustments.

These and other objects and features of our invention will be more fully understood upon reference to the following detailed description taken in connection with the accompanying drawings, and the scope of our invention will be fully pointed out in the appended claims.

In said drawings Fig. 1 is a perspective view of a display board structure embodying certain features of the present invention; Fig. 2 is a transverse section of the same taken on a plane indicated by the line 2-2 of Fig. 1; Fig. 3 is a partial vertical section of one of the supporting legs of the structure secured to its supporting screw which in turn is threaded into its post; Fig. 4 is a perspective view of the screw employed in the structure of Fig. 3; Fig. 5 is a view similar to Fig. 3 illustrating a post, its screw, and a connected brace; Fig. 6

is a perspective view of the screw employed in the structure of Fig. 5; Fig. 7 is a perspective view illustrating a modified leg and screw in connected relation; Fig. 8 is a partial sectional view illustrating a further modified leg and screw structure; Fig. 9 is a perspective view of a modified brace and screw in connected relation; Fig. 10 is a plan view of two bracing members showing the hook and slot connection by which the two are united; Fig. 11 is a section of the same taken on a plane indicated by the line 11-11 of Fig. 10; Fig. 12 is a rear view of a structure similar to that of Fig. 1 but showing somewhat longer legs and our improved backing and a modified system of bracing; Fig. 13 is a partial vertical section of one of the braces of the structure of Fig. 12, the plane of section being indicated by the line 13-13 of Fig. 12; Fig. 14 is a detail section of the braces of Fig. 12 taken at the point where they cross each other, the plane of section being indicated by the line 14-14 of Fig. 12; Fig. 15 is a partial sectional view of a connection at the lower end of the central braces of the structure of Fig. 12, the plane of section being indicated by the line 15-15 of Fig. 12; Fig. 16 is a perspective view of one of the coupling members used in the bracing system of Fig. 12; and Fig. 17 is a section through the backing, the section being taken on the line 17-17 of Fig. 12. Throughout these views like characters refer to like parts.

Referring to the drawings in detail, 20, 21, 22, 23, 24 and 25 designate uprights of the main frame structure. These uprights are composed of angle iron, as clearly illustrated. The end members 20 and 25 are extended so as to provide legs 26 and 27. All these uprights have flanges which lie in the same plane, and other flanges which extend outwardly from that plane. When assembled, the outstanding flanges of the members 21 and 22 abut against each other, and in like manner the corresponding flanges of members 23 and 24 abut against each other. In the preferred construction, the members 20 and 21 form the sides of a section. The other members of the section are the strip 28 and the angle bar 29. The former is secured to the backs of the co-planar flanges in any suitable way, as by welding or riveting or bolting. In like manner, the angle bar 29 has its vertical flange secured to the co-

planar flanges of the members 20 and 21. As clearly shown, the member 28 is near the top of the section, and the member 29 is at the bottom of the same. The connection of 5 the member 29 to the members 20 and 21 may be made in any preferred way, just as in the case of the member 28. The central section of the frame is made up of the members 22 and 23, and an upper member 30 10 and a lower member 31. These members are secured in the same way as the members of the previously described section. Similarly, the third section comprises the upright members 24, 25, the upper member 32 and 15 the lower angle bar 33. The members of this section are secured together in the same manner as the members of the first described section. It will be noted that the members 28, 30 and 32 are aligned, and in like manner members 29, 31 and 33 are in aligned 20 relation. The outstanding flanges upon the various upright members are apertured at both their upper and lower ends. A rod 34 extends through the apertures at the upper 25 ends and is provided with threaded ends and cooperating nuts 35. In like manner a rod 36 extends through the apertures in the uprights just beneath the angle bar members 29, 31 and 33, and is similarly provided with 30 threaded ends and cooperating nuts 37. By screwing the nuts 35 and 37 upon their respective rods, the various sections of the main frame are forced together. For shipping purposes, the frame may be "knocked 35 down" by removing the rods 34 and 36. This leaves the three sections as separate units, and they may be so shipped. If bolts are used to join the different members of the sections, each section may be further 40 "knocked down" by removing the bolts, and then the various members which go to make up the sections can be shipped as bars and rods. In either case, whether shipped as sections or shipped as bars and rods, it is possible 45 to produce a compact package or bundle for shipment.

The main frame may be variously braced. In ordinary practice, it is set up so as to occupy a vertical plane, or one closely approaching the vertical. Two systems of 50 bracing are illustrated, one being that of Fig. 1 and the other that of Fig. 12. In the former of these, the main bracing members 38 and 39 are secured at their forward 55 ends to the members 20 and 25 at points well up toward the upper ends of these members and their rear ends extend down to the ground or support upon which the structure is mounted. In association with these main 60 braces 38 and 39, we also preferably employ two cross braces 40 and 41. These are connected together at their center and at their opposite ends to the main braces 38 and 39, as clearly illustrated. It is also preferable 65 to employ auxiliary braces 42 and 43 which

extend between the main braces 38 and 39 and the main frame members 20 and 25 respectively. Obviously, these various braces should be connected to the main frame and to each other in such a manner that they 70 may be readily disconnected for shipping purposes and then again connected when the structure is set up.

Ordinarily, such connections would be made by bolts and nuts. However, we have 75 illustrated in Figs. 10 and 11 a preferred connection for use between the main braces 38 and 39 on the one hand, and the upper ends of the cross braces 40 and 41 on the other. As clearly shown in these figures, 80 the main brace 39 is provided with an elongated opening 44 which is of such size as to readily pass the hook 45 upon the end of the member 41 when the latter is presented in the dotted line position of Fig. 10. Once 85 the hook 45 has been passed through the opening 44, the member 41 may be moved to the full line position of Fig. 10. When in this position, the inside of the end of the hook bears firmly against a side of the hole 90 44 which forms a seat for the hook. When the parts are in the full line position of Fig. 10, the member 41 is locked against removal from the member 39. This form 95 of connection is used not only to connect members 39 and 41 but also members 38 and 40. When the cross braces 40 and 41 have their hooks properly seated in the members 38 and 39 then they may be secured together at the point of intersection 100 and secured to the braces 39 and 38 respectively, at their lower ends by means of bolts and nuts. Although this form of connection has been restricted in the first system 105 of bracing—that of Fig. 1—to the particular members mentioned, yet it will be understood that the same might be employed in connecting other members of the structure together. Such uses will readily suggest themselves to workers in this art. At 110 this point it may also be stated that the same form of connection is used in the bracing system of Fig. 12 in connecting the similar members 38' and 40' on the one side and 39' and 41' on the other.

Ordinarily, the main frame and its supporting bracing will be set up on the ground. In such case we arrange special supports for the frame legs and the lower ends of the main bracing members. These 115 include posts 46 which are externally spirally grooved and pointed so as to be readily screwed into the ground. Each post is provided near its upper end with a transverse opening 47 through which a bar may be 120 passed for use in screwing down the post. Each post is provided with a central bore extending down from its upper end and terminating in a threaded portion 48 near its lower end. This threaded bore is pro- 125

vided for the insertion of an adjusting screw to which the leg or brace is to be connected. In the case of those legs, such as the legs 26 and 27 of the structure of Fig. 1 and the corresponding legs 26' and 27' of the structure of Fig. 12, which have in each instance two flanges, we employ a screw 49 having an angular opening 50, into which the foot of the leg, for example, the leg 26, is to be seated. The screw 49 is provided with a head 51 and a shank 52, the latter being provided with threads 53 which cooperate with the threads 48 in the post 46 when the screw has been screwed into the latter. After the post 46 has been set and the screw 49 screwed down into it the required distance, the end of the leg, for example, the leg 26, is passed into the opening 50 and finally brought to its proper position. When so set, a screw 54, engaging with a threaded transverse opening 55 in the screw head 51, passes through an opening 56 in the lower end of the leg and firmly holds it in place. By this construction the leg and screw are firmly attached to each other. In the case of the screw which is to be used at the lower end of the main braces 38 and 39, we must employ one, designated 57, which has a different opening for the supporting member which it engages and to which it is to be secured. As clearly illustrated, screw 57 has a head and shank which are similar to those of the screw 49. The head, however, is provided with an opening 58 which takes the form of a slot extending completely across the head. This different construction is necessitated by reason of the shape of the braces 38 and 39. In this instance the screw which holds the brace and screw 57 together serves as a pivot about which the member 38 may be rotated through a considerable arc. This is to allow for adjustment of the brace at different angles to suit different elevations and conditions of the ground upon which the structure is being set up.

In practice, the posts 46 are first screwed into the ground, then the screws 49 and 57 are screwed into the appropriate posts, and adjusted by screwing them more or less into the posts, as may be required to give the proper elevations. Then the legs and braces are connected to the screws and the structure is in final position, fully set up and properly braced.

Obviously, instead of having the lower end of the legs 26 and 27, or 26' and 27', reduced so as to leave two angularly disposed flanges, requiring the angular opening 50 in the screw 49, we may cut away one of the flanges so as to provide the modified leg 26^a, shown in Fig. 7, and then provide the screw 49 with an opening 59 which extends into the top of the head and occupies but a single plane.

Again, instead of running the end upright members 20 and 25 down beyond the transverse members 29, 31 and 33, so as to provide legs, we may terminate the end member at the level of the members 29, 31 and 33, as clearly illustrated in Fig. 8, where the upright member 25 terminates at the level of the transverse member 33, and then provide a separate leg 60 in the form of a rod or pipe threaded into an opening in a casting 61 firmly secured to the outstanding flange of the associated transverse member 33, or 29, by any suitable means, as by screws 62, and in such case the leg 60 would cooperate as before with a screw 63 similar to the screws 49 and 57, but having a detachable head in the form of a sleeve 64, which is secured to the shank of the screw by a transverse screw 65 extending through a threaded opening in the sleeve and an opening in the shank of the screw 63. The means for connecting this screw 63 to the leg 60 is furnished in the instance illustrated by the same sleeve 64 and a screw 66 extending through a threaded opening in the sleeve and an opening in the leg 60. With this construction, the rod 36 of the structure of Fig. 1 would be replaced by a shorter rod 67, which would extend only far enough to take in the outstanding flanges of the members 23 and 24 on the one hand, and of the members 21 and 22 on the other, as clearly indicated in Fig. 8. In this instance, nuts 68 upon the ends of the rod 67 would be used to draw the different sections together.

As a further modification, the main braces 38 and 39 may be modified to have the shape of the brace 69, as illustrated in Fig. 9, and then the screw 49, having the angular opening 50, may be used in the rear posts 46.

Obviously, the frame structure which we have devised may be used to support any sort of display device. In some instances we may mount upon the same the display frames of our prior Patent No. 1,557,230, previously referred to. In such case we preferably locate a backing 70 upon the rear of the frame members, as clearly shown in Fig. 12. Preferably, the backing 70 is composed of a plurality of sections. In the present instance, three sections, designated 71, 72 and 73 are employed. The backing is thus divided into sections so as to enable the same to be shipped in a "knocked down" condition and then assembled at the point of installation. The adjacent edges of the backing sections are bent back upon themselves and the resulting folds interleaved. This structure is illustrated more particularly in Fig. 17 where the section 72 is bent back to form a fold 74 and the section 73 is bent back to form a fold 75. The folds 74 and 75 are interleaved as there clearly shown, and a bolt 76 is passed through

aligned openings in the overlapping portions of the sections and folds, and the same are firmly held together by an associated nut screwed down upon the end of 5 the bolt. Any desired number of bolts 73 and associated nuts may be employed and they may be variously located, one arrangement being shown particularly in Fig. 12. Where the sections are thus assembled and 10 secured they make a solid back which in turn is secured to the various members of the frame in any suitable way, as by means of the bolts 77. As clearly shown, these bolts connect the back to the frame members 20, 21, 22, 23, 24, 25, 29, 31, and 33. They too may vary in number and may 15 be variously located, an illustration being furnished by the arrangement in Fig. 12. When assembling the structure, it will be 20 apparent that the backing 70 may be put in place upon the vertical frame members either before or after the bracing members are put in place, if the bracing system of Fig. 1 is used. If, however, the bracing 25 system of Fig. 12 is used, then obviously the backing 70 must be put in place before the bracing members are attached to the main frame.

In the structure of Fig. 12, we have 20 shown the same frame arrangement as in the structure of Fig. 1, but have made the legs 26' and 27' somewhat longer than the corresponding legs 26 and 27 of the structure of Fig. 1. In this instance, we have 30 also supplemented the bracing of the frame with a transverse bar 78 which is bolted, or otherwise secured, at its opposite ends to the legs 26' and 27'. In this instance, the legs 26' and 27' have the same 40 angular termination as the legs 26 and 27, and are seated in and secured to the screws 49 and posts 46 in the same way.

The bracing of the structure of Fig. 12 differs somewhat from that of the structure of Fig. 1. The main bracing members 38' and 39' correspond generally to the members 38 and 39. In like manner, the members 40' and 41' correspond generally to the similarly disposed members 40 and 41 50 upon the previously described structure. As before noted, the hook and eye connection of Fig. 10 is used to connect the upper ends of the tie rods 40' and 41' to the upper sections 38^a and 39^a of the main bracing members 38' and 39' respectively. The rods 40' and 41' are flattened out at their upper ends and given a hook shape so as to properly engage the openings in the laterally extending flanges of the sections 38^a and 39^a. The 60 upper end of the section 38^a has one flange cut away and the other flange extended vertically so as to fit against the rear of the backing section 73. A bolt 79 and associated nut serve to secure the upper end of the section 38^a to the backing section 73 and the

adjacent frame member 20. The upper section 39^a of the main bracing member 39' is similarly shaped and secured to the backing and main frame.

The bracing member 38' is provided with 70 a lower section 38^b. This section is curved at its lower end and terminates in a downwardly extending portion similar to that illustrated in Fig. 9. It is secured to the screw 49 and the associated post 46 in the 75 same way as in the case of the structure of Fig. 9 previously described. The main bracing member 39' is provided with a lower section 39^b which is shaped and supported in the same way as the section 38^b. The 80 lower sections 38^b and 39^b are connected together by a transverse bar 80 which is secured at its ends by bolts 80^a provided with cooperating nuts. The bolts pass through slots in the ends of the bar 80 and suitable 85 openings in the lateral flanges of the sections 38^b and 39^b. When the nuts are screwed down upon the bolts, the parts are firmly held together and the bar 80 assists the bars 40' and 41' in the lateral bracing of the 90 structure.

The sections 38^a and 38^b of the brace 38' overlap each other, as clearly illustrated in Fig. 13. Bolts 81, 82, 83 and 84 pass through 95 slots in the overlapping portions of the sections 38^a and 38^b and by means of associating nuts the two sections are firmly held together. As shown, the bolts 81 and 82 pass through one pair of registering slots, and the bolts 83 and 84 pass through a second pair of 100 registering slots. By these pin and slot connections the member 38' may be extended or contracted as may be required when setting up the structure. Obviously, the slots through which these bolts pass may be varied 105 in number and length and the number of bolts passing through each pair of registered slots may be varied. The bracing member 39' is similar in construction to the bracing member 38', and its sections are adjustable 110 in like manner by means of the similarly disposed bolts 85, 86, 87 and 88 operating in like registering slots.

As clearly indicated in Fig. 13, the bolt 83 serves also to secure the lower end of the 115 rod 41' to the main brace 38'. In like manner the bolt 87 serves to secure the lower end of the similar rod 40' to the main brace 39'. At the point where the rods 40' and 41' cross 120 each other they are flattened out and longitudinal slots provided in the flattened positions. A bolt 89 provided with a cooperating nut 90 extends through the slots in the members 40' and 41', and when the nut 90 is screwed down tight upon the bolt the rods 125 40' and 41' are firmly secured together.

Besides securing the rods 40' and 41' at their point of intersection, the bolt 89 firmly secures together two coupling members 91 and 92. As clearly shown in Fig. 16, coup- 130

ling member 91 is provided with a flattened portion 93 which is apertured at 94. The bolt 89 passes through the apertures 94 of the respective coupling members 91 and 92, and the flattened portions 93 are pressed together and held firmly with the rods 40' and 41' by the bolt 89 and nut 90. The coupling members 91 and 92 are each provided with a sleeve 95 which is interiorly threaded for the reception of the associated bracing rods 96^a and 96^b. The upper rod 96^a is threaded at its lower end into the upper coupling member 91 and is flattened at its upper end and bent down so as to provide a portion 97 which will fit against the rear of the backing section 72, and to which it is secured by any suitable means, as by means of a bolt 98 provided with suitable nuts. The lower rod 96^b is threaded at its upper end into the tubular portion of the lower coupling member 92, and its lower end is turned down so as to extend in a vertical direction. Here it is secured to the screw 63 and post 46 by sleeve 64 in the same way as previously described in connection with the post 60, shown in Fig. 8. At the point where the rod 96^b crosses the transverse bar 80, the latter is provided with a slot, and the former is flattened sufficiently to provide an aperture for a bolt 98 which, with an associated nut, is used to firmly secure the two members together. By reason of the threaded connections between the couplings 91 and 92 and the rods 96^a and 96^b, it is possible to provide a certain amount of adjustment of, and tension in, the lateral bracing members. When the nuts on the various bolts are properly tightened, it will be seen that a very substantial bracing of the structure is obtained.

Heretofore we have pointed out a number of alterations and modifications which may be made in the structure we have invented, and it will be apparent to those skilled in this art that other changes may also be made without departing from the spirit and scope of our invention. We therefore do not wish to be limited to the exact details disclosed, but aim to cover all such alterations and modifications as rightly come within the scope of our invention, by the terms of the appended claims.

What we claim and desire to secure by Letters Patent is:

1. In a structure of the class described, a main frame comprising a plurality of spaced vertical angle irons having flanges lying in a common plane and other flanges forwardly outstanding from said plane, transverse members secured to said vertical members holding the same in spaced relation, tie rods extending through said outstanding flanges, means on said rods for engaging certain of said outstanding flanges to stiffen the structure, and a backing secured to said first mentioned flanges, said backing comprising separate sections of sheet metal having interleaved folds and overlapping portions and bolts extending through registered openings therein and cooperating with associated nuts to secure the parts together with a weather proof joint.
2. In a structure of the class described, a main display board frame having legs, a suitable support upon which the feet of said legs rest, two rearwardly and downwardly extending main braces secured at their upper ends to said main frame, suitable supports for the lower ends of said braces, crossed brace rods connected at their opposite ends respectively to said main braces, an auxiliary support rearward of said main frame, and central tie rods connected at their adjacent ends to said crossed rods at their point of intersection and at their distant end to said main frame on the one hand and to said auxiliary support on the other.

Signed at Chicago, Illinois, this 2nd day of June, 1924.

WILLIAM A. LEU.
EDWARD E. LEU.
